PIPE CLEANING APPARATUS

Henry Ford, Philadelphia, Pa.

Application May 16, 1933, Serial No. 671,397

2 Claims. (Cl. 15—104.03)

This invention appertains to new and useful improvements in guide and water drain means for pipe cleaning mechanisms and more particularly to water pipes which frequently become clogged by accumulations from water passing therethrough. At present, in most large cities, a considerable fee is required by the municipality before a street can be opened to repair service pipes. It is the principal object of the present invention to provide means whereby a service pipe from the consumer's end to the street main can be cleaned in an efficient and inexpensive manner.

An important object of the invention is to provide a pipe cleaner guide and water drain device, which will permit the convenient insertion of a cleaning element into a service line and at the same time take care of the inflow of water.

These and various other important objects and advantages of the invention will become apparent to the reader of the following specification.

In the drawings:—

Figure 1 represents a side elevational view of the entire apparatus.

Figure 2 represents a top plan view of the reel and cleaning element rotating assembly.

Figure 3 represents a vertical sectional view taken substantially on line 3—3 of Figure 2 with the exception of the motor and without showing the cleaning element.

Figure 4 represents a sectional view taken substantially on line 4—4 of Figure 2.

Figure 5 represents a side elevational view, partly in section, of the cleaning element feed means.

Figure 6 represents an enlarged fragmentary longitudinal sectional view through the water drain-out barrel.

Figure 7 represents a cross sectional view taken substantially on line 7—7 of Figure 6.

Figure 8 represents a side elevational view, partly in section, showing the driving handle.

Figure 9 represents a side elevational view of the cleaning element.

Figure 10 represents a cross sectional view taken substantially on line 10—10 of Figure 9.

Figure 11 represents a longitudinal sectional view through a portion of the cleaning element.

Referring to the drawings wherein like numerals designate like parts, it can be seen in Figures 1, 2 and 3 that the reel and rotating means are generally referred to by the numeral 5 and consist of a chassis frame 6 having wheels 7 thereon for support upon the trackway 8. A triangu-

lar shaped frame 9 is located at one end of the frame 6 and slightly inwardly of the opposite end is located another triangular shaped frame 10, while at this end of the chassis frame 6 is mounted the electric motor 11, the armature shaft of which is equipped with a pinion gear 12 in mesh with the large gear wheel 13 which is secured to the rotating frame 14. This frame 14 is provided with end trunnions 15—16, the trunnion 15 being disposed through a bearing in the frame 10, while the trunnion 16 is hollow and is disposed through a bearing in the frame 9. The trunnion 16 extends a substantial distance beyond the outside of the frame 9 and has set screws 17 thereon which can be operated to clamp the cleaning element, generally referred to by numeral 18, to the trunnion 16. The weight of the assembly is substantially equally divided on each side of the frame 10 and, therefore, a suitable handle 19 is provided on this frame 10 whereby the assembly 20 can be easily transported manually from place to place.

Extending transversely through the frame 14 is the shaft 20 having the cleaning element reel 21 thereon. The ends of this shaft 20 project 25 beyond the opposite sides of the frame 14 and are polygonally formed to accommodate a crank 22 whereby the reel can be rotated manually for retracting the cleaning element 18.

The foregoing describes the assembly 5. Numeral 23 generally refers to the water drain-off and feed means and this consists of a barrel 24 to which one end of an elongated sleeve 25 connects, as at 26. This sleeve 25 has a tube 27 extending therefrom and this is secured and packed at its opposite end within the end *a* of the barrel 24 which connects to the water service pipe 28, as shown in Figure 1 of the drawings. A connecting boss 29 is provided at the intermediate portion of the barrel 24 and to this can be connected the drain pipe 30.

An elongated tubular member 31 is slidably disposed in the sleeve 25 and has a set screw 32 at its outer end for clamping the cleaning element 18 thereto during the operation of feeding the cleaning element through the tube 27 and service pipe 28. The member 32 is provided with a grease cup 31*a* so as to maintain the same constantly charged with grease to prevent the seepage of water from the barrel 24 between the cleaning element and the said member 32.

Slidable on the cleaning element 18 is a driver 33 of tubular construction, the same being provided with a head 34 and obviously, when the cleaning element 18 has been secured in the

member 31, after the member 31 has been retracted to its full extent outwardly, the driver 33 can be used for driving the tubular member 31 inwardly and obviously, this carries with it 5 the cleaning element which has been secured by the set screw 32 to the tubular member 31. After the tube 31 has been driven all the way into the sleeve 25, the screw 32 is released, and the tube is moved outwardly on the element 18 from the 10 sleeve 25, where it is again secured to the cleaning element and the operation repeated by hammering against the outer end of the tubular member 31 with the driver 33. This operation is continued until the street main is reached and at 15 this point, considerable water flows into the barrel 24, passes into the tube 27, but quickly passes outwardly through the perforations 35 therein to the barrel 14 and out of the barrel 14 by way of the drain pipe 30, so that very little of the 20 water can get into the sleeve 25. The sleeve can be packed at its outer end, as at 36, and the outer end of the member 31 can be greased to further prevent water from escaping, should a slight amount get this far along the cleaning element. During the operation of feeding the 25 cleaning element, the cleaning element is being rotated, as is the tubular rod 31 and obviously the cleaning operation is taking place continuously from the time the cleaning element enters the 30 service pipe 28 until it reaches the main. It will be observed that the perforated tube serves as a guide between the sleeve 25 and the service pipe connection 8 for guiding the cleaning element into the service pipe.

35 The cleaning element 18 is clearly shown in detail in Figures 9, 10 and 11, and this consists of an elongated metallic strand (preferably metallic) 38 wrapped by a coil 39 of wire or some

other suitable material, with the convolutions in snug relation. This strand 38 is fixed with respect to the coil 39 and preferably has no sliding action therein.

While the foregoing specification sets forth the 5 invention in specific terms, it is to be understood that numerous changes in the shape, size and materials may be resorted to without departing from the spirit and scope of the invention as 10 claimed hereinafter.

Having described the invention, what is 15 claimed as new is:—

1. Feed and drain means for pipe cleaning apparatus consisting of a barrel, a cleaning element receiving guide tube extending through the barrel and having perforations at its portion within the barrel, means at one end of the barrel for connecting the same to a service pipe, and means at the opposite end of the tube whereby a cleaning element can be fed into the said perforated 20 tube and guided by said tube into the service pipe, said barrel having a water outlet.

2. Feed and drain means for pipe cleaning apparatus consisting of a barrel, a cleaning element receiving guide tube extending through the 25 barrel and having perforations at its portion within the barrel, means at one end of the barrel for connecting the same to a service pipe, and means at the opposite end of the tube whereby a cleaning element can be fed into the said perforated tube and guided by said tube into the service pipe, a water outlet for the barrel, said last mentioned means comprising an elongated tubular member through which the cleaning elements can be disposed and means on the said 30 tubular member for securing the cleaning element therein.

HENRY FORD.
